DESIGN FOR AN ILLUMINATED ADVERTISING SIGN OR SIMILAR ARTICLE

Isidore Holsman, Chicago, Ill.

Application December 14, 1934, Serial No. 54,431

Term of patent 7 years

To all whom it may concern:

Be it known, that I, Isidore Holsman, a citizen of the United States, and a resident of the city of Chicago, county of Cook, and State of Illinois, have invented a new, original, and ornamental Design for an Illuminated Advertising Sign or Similar Article, of which the following is a specification, reference being had to the accompanying drawing, forming a part thereof.

In the drawing, the figure is a perspective view of an illuminated advertising sign showing my new design.

I claim:

The ornamental design for an illuminated advertising sign or similar article, as shown.

ISIDORE HOLSMAN.
